UNITED STATES PATENT OFFICE.

HENRY JUDSON HOLDREDGE, OF WILKES-BARRE, PENNSYLVANIA.

ELECTRICAL SNAP-SWITCH.

1,353,589.

Specification of Letters Patent. Patented Sept. 21, 1920.

Application filed June 12, 1920. Serial No. 388,434.

To all whom it may concern:

Be it known that I, HENRY JUDSON HOLDREDGE, a citizen of the United States, residing at Wilkes-Barre, in the county of Luzerne and State of Pennsylvania, have invented certain new and useful Improvements in Electrical Snap-Switches, of which the following is a specification, reference being had to the accompanying drawings.

10 This invention relates to electrical snap switches and more particularly to that type of snap switch adapted to automatically disconnect current from the source of power.

An important object of the invention is 15 to provide a switch of the above character which will automatically extinguish lights upon the closing or opening of a door as desired.

20 A further object of the invention is to provide a device of the above character which is extremely simple in construction and operation and which may be cheaply manufactured.

25 These and other objects I obtain by the combination and arrangement of the parts illustrated in the accompanying drawings, in which:

30 Figure 1 is a side elevation of a section of a door casing and door, showing my switch applied thereto for use.

Fig. 2 is a plan view of my switch, portions being broken away for the purpose of illustration, and

35 Fig. 3 is an enlarged detail view showing the operating mechanism by means of which the snap switch is automatically operated by a door, window or other moving member.

40 Referring now more particularly to the drawings, in which like reference characters designate like parts throughout, my switch comprises a base 10 having mounted thereon a rotary snap switch 11 of the usual construction. The base 10 is provided with openings 12 by means of which the switch 45 may be attached to a suitable support. A casing 13 is provided through which the operating stem of the snap switch extends, the operating stem being provided exteriorly of the casing with an operating thumb piece 50 14. The switch may likewise be provided with the usual "on" and "off" signals, if desired.

55 The operating stem 15 of the switch has secured thereto, in any suitable manner, a cam 16, embodying diametrically opposed

cam shoulders 17. A plate 18, or master plate, is rotatably mounted upon the stem adjacent the cam 16 and has pivotally mounted thereon a dog 19. This dog embodies a shoulder 20 adapted to engage the 60 cam shoulders 17 of the cam 16, and is held in firm engagement with the cam by means of a spring 21 which engages the dog upon the reduced extension 22 thereof, and the master plate 18 upon an integral hook 65 shaped extension 23. The spring 21 is of the compression type and constantly forces the shoulder 20 of the dog 19 into engagement with the cam 16. Binding of the shoulder 20 upon the cam 16 is prevented 70 by means of the shoulder 19' formed on the dog which engages against one side of the master plate 18.

The master plate 18 is provided with an elongated slot 24 adapted to receive a pin 75 25' rigidly mounted in a longitudinally shiftable bar 25. This bar is normally held in the position shown in the Figs. 2 and 3 by means of a tension spring 26 secured to the bar as at 27 and to the casing 13 as at 80 28. The ends of the bar are slidably mounted in suitable openings formed in the side walls of the casing 13 and one end of the bar is provided with a cushioning element 29 formed of rubber or the like. 85

In the application shown in Fig. 1, the switch is secured to the frame 20 of the door in such a manner that the cushioning element mounted on the bar 25 extends into the path of the door 31 when closing, as indicated by the dotted lines on this figure. It will be obvious that when the door is completely closed the bar 25 is shifted longitudinally causing the master plate 29 to shift about its pivot and carry therewith the 95 spring 19. If the current is turned on through the switch and the cam is in the position indicated by the solid lines in Fig. 3, the shoulder 20 of the dog engages one cam shoulder 17 of the cam and shifts the 100 cam to the position shown by the dotted lines in Fig. 3. If, however, the lights have been turned off previous to the closing of the door and the cam is in the position indicated by the dotted lines in Fig. 3, the dog 19 exercises no effect whatever upon the cam, and the current remains turned off. It will therefore be seen that if the current is turned on it will be disconnected through the snap switch upon closing of the door. This de- 110

vice may be applied to either right hand or left hand opening doors by simply inverting the switch, and may be adapted for igniting the lights upon opening or closing the door 5 by simply altering the position of the cam shoulders by shifting the cam through 90° upon the operating stem 15 of the switch.

As many other changes of similar character and in the shape, size and arrangement 10 of the various parts herein shown may be readily made, I do not limit myself to the particular construction hereinbefore set forth, but may make any such changes without departing from the spirit of the invention or the scope of the subjoined claims: 15

Having now described my invention, what I claim is:

1. The combination with a rotary snap switch embodying the usual rotatable operating stem adapted when rotated to alternately place the switch in open and closed position and means for rotating said stem, of a cam secured to said operating stem and embodying a shoulder, a longitudinally 20 shiftable bar arranged adjacent said cam, yieldable means normally holding said bar in one position, and operating means connected with said shiftable bar to be shifted thereby and adapted to engage the shoulder 25 of said cam to shift the cam in one direction when the switch is in one position and inoperative to engage said shoulder when the switch is in the other position.

2. The combination with a rotary snap switch embodying the usual rotary operating stem adapted when rotated to alternately place the switch in open and closed position and means for rotating said stem, of a cam secured to said operating stem and embodying a shoulder, a longitudinally 30 shiftable bar arranged adjacent said cam, yieldable means normally holding said bar in one position, a plate rotatably mounted upon said operating stem and connected 35 with said shiftable bar to be oscillated thereby when the bar is shifted, and means carried by said plate for engaging the shoulder of said cam and shifting the same when the plate is oscillated when the switch is 40 in one position and inoperative to engage said shoulder when the switch is in the other position.

3. The combination with a rotary snap switch embodying the usual rotatable stem adapted when rotated to alternately place the switch in open and closed position and means for rotating said stem, of a cam secured to said operating stem and embodying a shoulder, a longitudinally shiftable bar 45 arranged adjacent said cam, yieldable means normally holding said bar in one position, a plate rotatably mounted upon said stem adjacent said member, a pivoted dog car-

ried by said plate, a spring holding said dog in engagement with said cam and means 50 connecting said plate and said bar whereby said plate is oscillated when the bar is shifted, said dog being operative to engage the shoulder of said cam when the switch is in one position and inoperative to engage 55 said shoulder when the switch is in the other position.

4. The combination with a rotary snap switch embodying the usual rotary operating stem adapted when rotated to alternately place the switch in open and closed position and means for rotating said stem, of a cam secured to said operating stem and embodying a pair of diametrically opposed cam shoulders, said shoulders being disposed 60 at an angle of 90° to the contact blades of the switch, a longitudinally shiftable bar arranged adjacent said cam, yieldable means normally holding said bar in one position, a plate rotatably mounted upon said stem 65 adjacent said cam and embodying a slot, a pin mounted upon said bar and engaging in said slot, and a pivoted spring pressed dog carried by said plate and engaging said cam, said shoulder being positioned to be engaged by said dog when the switch is in one 70 position and being so positioned as to be free from engagement by said dog when the switch is in the other position.

5. The combination with a rotary snap switch embodying the usual contact blades and rotatable operating stem therefor, of a member secured to said stem embodying a pair of diametrically opposed cam shoulders, said shoulders being disposed at an 75 angle of 90 degrees to the contact blades of the switch, a longitudinally shiftable bar arranged adjacent said member, yieldable means normally holding said bar in one position, a plate rotatably mounted upon 80 said stem adjacent said member and provided with a slot, a pin mounted upon said bar and engaging said slot, a pivoted dog carried by said plate, a spring moving said dog toward said cam and a shoulder formed 85 on said dog and engaging said plate to limit the movement of said dog toward said cam.

6. The combination with a rotary snap switch embodying the usual contact elements, a rotatable operating stem whereby 90 said contact elements may be shifted into open and closed positions and means for rotating said operating stem, of additional means for rotating said operating stem, said means being operative when the switch 95 elements are in one position and inoperative when the switch elements are in the other position.

In testimony whereof I hereunto affix my signature.

HENRY JUDSON HOLDREDGE.
